UNITED STATES PATENT OFFICE.

JOHN WARREN SMITH AND GEORGE UPTON HARN, JR., OF COLUMBUS,
OHIO.

CUTTING ATTACHMENT FOR PRINTING-PRESSES.

No. 816,945.

Specification of Letters Patent.

Patented April 3, 1906.

Application filed February 29, 1904. Serial No. 195,772.

To all whom it may concern:

Be it known that we, JOHN WARREN SMITH and GEORGE UPTON HARN, Jr., citizens of the United States, and residents of Columbus, in the county of Franklin and State of Ohio, have invented a new and useful Improvement in Cutting Attachments for Printing-PresSES, of which the following is a full, clear, and exact description.

Our invention relates particularly to that class of printing-presSES in which material from a roll is fed continuously to printing devices and is then systematically cut after an impression has been made thereon; and the invention further relates to an improvement on the press of the above-named class for which Letters Patent were granted to us December 15, 1903, No. 747,009.

The purpose of the invention is to provide a knife so mounted with reference to the frame of the machine and with relation to the feed for the paper that as the knife and its support approach the cutting position of the knife said parts are automatically fed forward by suitable mechanism at the same rate of speed as that at which the paper travels, thereby insuring a clean cut when the knife is actually in cutting action without danger of buckling the paper.

A further purpose of the invention is to provide for an automatic movement of the knife from the paper to permit the further outward movement of the latter, together with an automatic return movement of the knife-support at the same time.

Another purpose of the invention is to provide an improved and simple means for supporting and operating the knife and likewise to provide adjustable bearings for the feed.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a side elevation of the improved press, showing the knife and carrier in its inner or normal position. Fig. 2 is a longitudinal vertical section through the machine. Fig. 3 is a front elevation of the machine. Fig. 4 is an enlarged side elevation of the for-

ward upper portion of the frame of the machine and an end view of the knife and its support, illustrating the knife and the support in their outer positions, the knife about to be elevated, and the support for the knife about to be released to return to the normal position shown in Fig. 1; and Fig. 5 is a detail front elevation of the knife, a portion of the frame, and the supports for the knife, the knife being shown in its lower or cutting position, the knife being illustrated in Fig. 3 in its upper position.

The frame of the machine consists of two cheek-pieces united by a bottom plate X. These cheek-pieces each consist of a main vertical section A and a forward extension A' from their upper edges. The extensions A' from the cheek-pieces A are practically in two sections—namely, an inner section a and an outer section a', the inner section a being of greater vertical depth than the outer section a', and the outer section a' extends from the upper outer edge of the section a with more or less of an inclination, as is shown in Figs. 1 and 2. A recess 10 is produced in the upper edge of each extension A at that point where the inner section a connects with the main upright section A of the cheek-pieces, and in these recesses 10 bearings 11 are mounted to slide. These bearings 11 are adapted to receive the trunnions 12 of a printing-roller B, which may be of any desired construction, and the adjustment of the bearings 11 is regulated by set-screws 13. A recess 14 is made in the section a of each extension A' from the main section A of each cheek-piece, and in each recess 14 a bearing 15 is mounted for vertical movement. The adjustment of the boxes 15 is accomplished by means of adjusting-bolts 17, which are passed through the closing-plates 16 to an engagement with the bottom portions of the boxes 15, and upper bolts 19, which pass through the bridge or cross bars 18 to an engagement with the upper edges of the said bearings 15. The bearings 15 are adapted to receive the trunnions 22 of a bed roller or cylinder C, which nearly engages with the printing-cylinder B, being located directly beneath it, as is shown in Fig. 2.

While the printing-cylinder B may be revolved by power in any suitable manner, we have illustrated the said cylinder as provided with a crank-arm B', secured at the outer

end of one of its trunnions, so that the said cylinder B may be operated by hand. On the same trunnion to which the handle or crank-arm B' is secured a gear 23 is fastened at the outside of the cheek-piece at that side of the machine, and the said gear 23 meshes with a similar gear 24, correspondingly secured to the trunnion 22 for the bed-cylinder C, as is shown best in Fig. 1, so that by the operation of the printing-cylinder B the bed-cylinder C is correspondingly rotated.

Two feed-rollers—an upper one 25 and a lower one 26—are mounted to turn at the forward or delivery end of the machine, the roller 25 being provided with trunnions 25^a and the roller 26 with trunnions 26^a. The feed-roller 25 is located opposite the front lower portion of the cylinder B, being practically mounted at the upper section *a* of the extension A' from the cheek-pieces, while the lower roller 26 is journaled in the inner or deeper section *a* of the said extension, as is clearly illustrated in Fig. 2 and indicated in Fig. 1. In front of the two forward feed-rollers 25 and 26, opposite the point where the two rollers substantially engage, a table 27 is formed, which extends from the lower edge of one member *a* of the cheek extension A' to the opposing member or section *a*, as is shown also in Figs. 1 and 2. A third feed-roller 28 is employed, and this third feed-roller 28 is journaled in the cheek-pieces A in such manner that it will engage with the bed-roller C at the upper rear portion thereof, as is illustrated in Fig. 2. The rear feed-roller 28 is journaled in what may be termed "swinging and adjustably-mounted bearings" 29. Under this form of bearing, into the hubs of which the trunnions 28^a of the rear feed-roller 28 are mounted to turn, the said feed-roller may be adjusted to or from the bed-cylinder C or may be adjusted upward or downward tangentially to the said bed-cylinder. The upper forward feed-roller 25 is provided with a swinging adjustable bearing 29^a, so that it may be adjusted to or from its mating or lower feed-roller 26; but the trunnions 26^a of the lower forward feed-roller 26 are simply journaled in the frame, and this roller 26 does not need to be adjustable.

At a suitable point between the upper and lower ends of the main sections A of the cheek-pieces of the frame recesses 31 are formed in the rear edges of the said main sections A, adapted to receive the trunnions 30^a of a spool 30, as is shown in Figs. 1 and 2; the said spool being removable from the said recesses. On the spool 30 the paper 32 to be printed upon is wound, and this paper is led forward between the rear feed-roller 28 and the bed-roller C, then between the bed-roller C and the printing-roller B, and the paper after receiving its impression is passed through the forward feed-rollers 25 and 26 and over the table 27 to be acted upon by a

cutting mechanism located at the forward end of the machine.

The rear feed-roller 28 is driven by means of a pinion 34, which is secured to this trunnion at that side of the machine where the gearing 23 and 24 is located, and the pinion 34 meshes with the teeth of the gear 24. The forward feed-rollers 25 and 26 are driven in the following manner: A pinion 36 is mounted on the trunnion 25^a of the upper forward feed-roller 25 at the geared side of the frame, and this pinion 36 meshes with a pinion 38, located on the trunnions 26^a of the lower forward feed-roller 26, also at the geared side of the frame. The pinion 38 meshes with the teeth of the pinion 36, while the teeth of the pinion 38 meshes with the teeth of a pinion 39, located below it and mounted to turn on a stud 40, carried by the frame. The said pinion 39 meshes with the teeth of the gear 24, carried by the bed-roller C.

The cutting mechanism consists of a frame D and a knife E, which is carried by the frame. The frame is located at the forward upper portion of the machine at the terminal ends of the sections *a'* of the extension A' from the main portion A of the cheek-pieces, as is best shown in Figs. 1, 2, and 4. This frame extends from side to side of the machine and consists of an upper front plate 41, side members 42, with which the plate is integrally made or to which the plate is attached, and a lower cross-bar 43, extending from one side 42 to the other, having members 43^a, which extend rearwardly to a sliding engagement with the lower edge of the forward upper sections *a'* of the frame, as is also shown in Figs. 1, 2, and 4, together with rearwardly-extending arms 44, carried from the sides 42 of the frame, which arms 44 are mounted to slide in slideways or slots 45, produced in the said frame members or sections *a'*, as is best shown in Fig. 4, and each of the arms 44 is provided with an outwardly-extending foot 46 at its inner end. Springs 47, as is best shown in Fig. 2, are attached to the inner faces of the said forward upper members *a'* of the frame and to the front plate 41 of the knife-carrying frame D, and a sufficient space is provided between the lower edge of the said front plate of the knife-carrying frame and the lower bar 43, as is clearly shown in Fig. 2, to permit the free outward passage of the printed end of the paper while the knife E, to be hereinafter described, is in its upper position, and when the knife is lowered it severs the printed portion of the paper into predetermined lengths. The knife E is located at the forward portion of its carrying frame D, and the cutting edge *e* of the said knife may be plain, but is preferably serrated or in scalloped form, as is illustrated in Figs. 3 and 5. The knife has guided movement on the frame by means of screws 48 or their equivalents, which pass through slots 130

49, produced in the knife and entering the front bar 41 of the knife-carrying frame D, and the said knife is adapted for movement parallel with its carrying-frame in an up and down direction and moves as does a parallel-ruler. Therefore the knife is supported by two links 50 and 51. The link 50, which is at what may be termed the "left-hand end" portion of the knife, is a plain link and is pivoted to the knife-blade at one end and to the upper end of the knife-carrying frame D at its opposite end; while the link 51, which is pivoted correspondingly to the link 50, is, however, located near what may be termed the "right-hand end" of the knife and is provided with a projection 52 of sufficient length to extend beyond the right-hand side of the machine and to be within the path of the handle B', operating the printing-cylinder, as the said handle is brought forward and is to be carried upward or at such time as when the said printing-cylinder has made practically a complete revolution, and the lower edge of the link 51 and the extension 52 therefrom is beveled from the pivotal portion of the link upwardly and outwardly, as is shown in Figs. 3 and 5.

A spring 53, secured to the right-hand cheek of the frame, (also shown in Figs. 3, 4; and 5,) engages with the upper face of the extension portion 52 of the link 51, which link 51 may be termed a "combined operating and supporting" link, and said spring 53 when the said extension 52 of the link 51 is not engaged by the handle B' acts to carry the knife-blade E upward to permit the free outward passage of the printed portion of the paper, the links being then in the position shown in Fig. 3. When the handle B', however, is brought forward and upward, it engages with the extension or projection 52 from the link 51 and raises the same, as is shown in Fig. 5, thus bringing the pivotal portion of the links practically to the vertical position shown in the same figure and causing the cutting edge of the knife to pass down over the bottom bar 43 of the knife-carrying frame to sever the paper or cut it into desired lengths, and the moment that the cut is produced the handle B' will have been carried by the extension or projection 52 from the link 51, and at such time the spring 53, asserting itself, will restore the links to their normal inclined position and will consequently carry the knife upward to its normal position, so as not to interfere with the continued outward passage of the printed portion of the sheet.

In order to prevent the printed paper from buckling back of the knife by reason of the action of the knife in cutting off a section of paper during the continuous feed of the paper at the rear of the knife at a time representing about that taken by a revolution of the printing-cylinder, the knife-carrying

frame D and the knife E are forced gradually forward at the same rate of speed as that at which the paper is fed, and when the knife-carrying frame is at its farthest outward movement the mechanism described for forcing a knife downward acts and the printed section of the sheet is severed. The knife, then immediately returns to its upper position, as has also been described, permitting the uninterrupted outward passage of the next printed section, and the outward actuating mechanism of the knife-carrying frame then permits the said frame to be drawn back to its normal or inner position by the direct action of the springs 47. This mechanism is as follows: A shaft 55 is mounted to turn in the extension sections a' of the members of the frame, the said shaft being located between the recess in which the knife-supporting frame has sliding movement and the upper feed-roller 25 for the paper, as is illustrated in Fig. 2. A cam 54 is secured to the said shaft 55 at each outer end. These cams are of the same formation and may be termed "snail-cams," as each cam is provided with a radial periphery concentric to the center of the shaft and extending one-half of the circumference of the cam, and the opposite peripheral portion of the cam is spirally formed or is gradually carried from the center of the shaft on radial lines, forming thereby an eccentric peripheral surface, connected with the true radial peripheral surface at one end by a shoulder 54a, as is clearly shown in Fig. 4. These cams are adapted to engage with the foot-sections 46 of the knife-carrying frame D, and when the knife-carrying frame is in its inner position (shown in Fig. 1) and the true radial or concentric peripheral surface of the cam is in engagement with the feet 46 of the said knife-carrying frame the cam has no influence whatsoever on the said knife-carrying frame; but as soon as the rise in the peripheral portion of the cam engages with the said feet 46 the knife-carrying frame is forced outward until when the greatest rise in the eccentric portion of the cam is in engagement with the said feet 46 of the knife-carrying frame D the said frame will be at the limit of its outward movement, as is shown in Fig. 4, at which time the knife is brought to cutting position. Just before the eccentric peripheral surface of the cam disengages from the said knife-carrying frame D the knife is carried upward, and immediately upon the said eccentric surfaces of the cams leaving the said knife-carrying frame D the springs 47 act to again bring the knife-carrying frame, with the knife, in the upper position to its inner or normal position with the feet 46 against the true radial concentric peripheral surface of the cams. The movement of the cams 54 is such that as the frame D is carried outward its movement is practically, if not exactly, the same as to speed as the speed at which the

paper is fed from the printing and the bed rollers. It will be observed by this movement that there is no possible buckling of the paper back of the knife-carrying frame, as 5 the action of cutting is quickly performed and the knife is quickly raised and the paper can continue to pass on and out through the bottom opening in the frame. The shaft 55 is driven by securing a pinion 56 on the outer 10 portion of the shaft between the frame and the right-hand cam, as is shown by dotted lines in Figs. 1 and 4, which pinion meshes with the pinion 36 on the right-hand trunnion of the upper forward feed-roller 25, so 15 that the movement of the cam is the same as the movement of the pinions controlling the feed mechanism.

Any suitable inking device may be employed; but as shown in the drawings it 20 consists of a font 57, a take-up roller 58, a receiving-roller 60, a transfer-roller 62, a distributing-roller 70, and the main inking-rollers 75 and 76. The roller 76 carries on one of its trunnions a gear 79 in mesh with 25 the gear 23 of the cylinder B and the gear 61 of the receiving-roller 60, and with the gear 61 meshes the gear 72 on the trunnion of the distributing-roller 70. The trunnion of the distributing-roller 70 carries a cam 73, having a spiral raceway 74, with which a fixed pin 75 engages, so as to impart end movement to said roller. On the gear 61 is eccentrically mounted an arm 67, which is pivotally attached to the trunnion of the transfer-roller 30 62, and on said trunnion is a pawl 69, which engages with the ratchet-wheel 59 on the trunnion of the take-up roller 58, whereby the take-up roller 62 will be alternately moved into engagement with the take-up 35 40 roller 58 and receiving-roller 60 and at the same time the roller 58 will be revolved. The rollers 6, 70, 75, and 76 are mounted in adjustable swinging bearings similar to those in which the feed-rollers 25 and 28 are 45 mounted.

It will be observed that the operation of the knife is thoroughly automatic, and, as has been heretofore stated, the knife can act to cut the paper without retarding its feed and 50 without causing the paper to buckle in the slightest degree at the rear of the knife during its cutting action.

Having thus described our invention, we claim as new and desire to secure by Letters 55 Patent—

1. In a printing-press, a main frame, a printing-cylinder mounted in the frame, a paper-feed device also mounted in the frame, a sliding and spring-pressed auxiliary frame 60 mounted in the main frame, a knife mounted for cutting and withdrawal movements on the said auxiliary frame, which movements are at an angle to the sliding movement of the auxiliary frame in the main frame, an actuating device for the said auxiliary frame

controlled by the said feed, a tension device for holding the knife in one position, and means for forcing the knife to another or cutting position from the printing-cylinder, as described. 70

2. In printing-presses, a main frame, feed devices for the paper mounted in the main frame, an auxiliary frame having sliding and tension-controlled movement in the main frame, a knife connected with the said frame by links, one of the links being provided with an extension, a spring bearing on the extension-link, normally holding the knife in an upper position, means for engaging the extension from the supporting-link of 80 the knife to force the knife down to cutting position, and means for imparting an advance movement to the auxiliary frame at the time the knife is in its lowermost or cutting position and at practically the same speed as the speed at which the paper is fed, as described. 85

3. In printing-presses, a main frame, feed devices for the paper, a sliding and spring-pressed auxiliary frame mounted in the main 90 frame, a support over which the paper is adapted to pass, cams arranged for advancing the said auxiliary frame and releasing the same at intervals, a driving connection between the said cams and the feed devices, a tension-controlled knife mounted to slide on the auxiliary frame, links pivoted to the auxiliary frame and to the knife, one of the links having an extension, and a movable member for engaging the extension of the link to move the knife into cutting position, as described. 95

4. In printing-presses, a main frame, a tension-controlled auxiliary frame mounted to slide in the main frame, means for operating the auxiliary frame, a knife carried by the auxiliary frame, links in parallel order pivoted at one of their ends to the auxiliary frame and at their other ends to the knife, guides for the knife, an extension from one of the said links, for the purpose described, a movable member for engaging the extension of the link to operate the knife, a spring for returning the knife to inoperative position. 105

5. In printing-presses, a main frame, a tension-controlled auxiliary frame mounted to slide in the main frame, a knife carried by the auxiliary frame, links in parallel order pivoted at one of their ends to the auxiliary frame and at their other ends to the knife, 110 guides for the knife, an extension from one of the said links, a printing-cylinder mounted in the said frame, an arm from the printing-cylinder arranged for engagement with the extension from the said link, a spring having 115 downward bearing on the said extension, the lower edge of the extension of the link being beveled for engagement with the said arm from the said printing-cylinder, whereby to raise and lower the knife, as set forth. 120 125 130

6. In printing-presses, a main frame, a tension-controlled auxiliary frame mounted to slide in the main frame, a knife carried by the auxiliary frame, links in parallel order pivoted at one of their ends to the auxiliary frame and at their other ends to the knife, guides for the knife, an extension from one of the said links having a beveled edge, a crank-arm adapted for engagement with the extension from the said link, a spring having downward bearing on the said extension of the link, feed devices and means for imparting an intermittent movement to the auxiliary frame from the feed devices, as specified.
7. In a printing-press, a main frame, a tension-controlled auxiliary frame mounted to slide in the main frame, a feed device for the material, cams for operating the auxiliary frame, means for operating the cam from the feed device, a knife having sliding and guided movement on the auxiliary frame, links pivoted to the knife and to the auxiliary frame, one of the links having an extension, a crank-arm adapted to engage the extension of the link to operate the knife, and a spring engaging the said extension of the link.
8. In a printing-press, a main frame, a knife-frame carried thereby, a knife having guided movement on its frame, links pivoted to the knife-frame and to the knife, one of the links having an extension, a spring engaging the extension of the link, and a crank-arm adapted to engage the said extension of the link to operate the knife.
9. In a printing-press, a main frame, feed-rollers mounted in the frame an auxiliary frame mounted to slide in the main frame in front of the feed-rollers and provided with projections at its sides, a spring secured to the main frame and to the auxiliary frame, cams engaging the projections of the auxiliary frame, means for operating the cams from the feed-rollers, and a reciprocating knife carried by the auxiliary frame.

In testimony whereof we have signed our names to this specification in the presence of two subscribing witnesses.
